UNITED STATES PATENT OFFICE

2,266,862

COUNTING APPARATUS

Virgil S. Hardey, Oak Park, Ill.

Application August 21, 1940, Serial No. 353,480

3 Claims. (Cl. 235—132)

My invention relates, generally, to counting apparatus, and it has particular relation to the operation counting apparatus.

An object of my invention is to provide for operating a member from one position to another on the receipt of a first impulse and then to move the member back to its original position on the receipt of a last impulse of a number of impulses.

Another object of my invention is to provide for adjusting the number of impulses required to effect the movement of the member from and to its initial position.

A further object of my invention is to provide inertialess means for counting a number of revolutions of a disc in a new and improved manner.

Other objects of my invention will, in part, be obvious and in part appear hereinafter.

My invention is disclosed in the embodiment thereof shown in the accompanying drawings and it comprises features of construction, combination of elements and arrangement of parts which will be exemplified in the construction hereinafter set forth and the scope of the application of which will be indicated in the appended claims.

For a more complete understanding of the nature and scope of my invention, reference can be had to the following detailed description taken in connection with the accompanying drawings in which:

Figure 1 is a view, in front elevation, of a counting mechanism constructed in accordance with this invention;

Figure 2 is a view, in side elevation, of the mechanism shown in Figure 1;

Figure 3 is a view taken along the line 3—3 of Figure 2;

Figure 4 is a detail sectional view taken along the line 4—4 of Figure 1; and

Figure 5 diagrammatically illustrates the arrangement of the counting mechanism as shown in Figures 1 through 4 with an inertialess control mechanism.

Referring now particularly to Figure 1 of the drawings, it will be observed that the reference character 10 designates, generally, a counting mechanism in which the present invention is embodied. The mechanism 10 is mounted on a face plate 11 of suitable insulating material, such as "Bakelite" and is surrounded by metal trim 12. A metal ring 13 is provided within the trim 12 to facilitate securing certain parts on the back of the face plate 11 as will be apparent hereinafter.

Rotatably mounted with respect to the face

plate 11 is an indicating disc that is shown generally at 14. The disc 14 is provided with semi-cylindrical apertures 15 around its periphery certain of which are numbered as indicated at 16.

5 The indicating disc 14 is provided with a detent 17 which is arranged to abut a stop 18 that depends from a cam member 19 which projects through an opening 20 in the face plate 11. The manner in which the cam 19 is mounted on the 10 rear of the face plate 11 will be set forth in detail hereinafter. The cam 19 is provided with a cam surface 21 with which the outer end of the detent 17 cooperates to raise the cam member 19 when the indicator disc 14 is rotated in a clockwise direction just prior to engagement of the 15 detent 17 with the stop 18. The cam member 19 is provided with a similar cam surface 22 on the opposite side of the stop 18 for a purpose which will be presently apparent.

20 A manual resetting knob 23 is mounted for rotation with the indicator disc 14 and is provided for manually rotating the same.

Mounted for rotation with respect to the indicator disc 14 under certain circumstances is a 25 control arm 27. The control arm 27 has an aperture 28 therein which registers with the numerals 16 on the indicator disc 14 so as to quickly identify the particular semi-cylindrical opening adjacent to which the control arm 27 is positioned. 30 The knob 29 is mounted on the control arm 27 to permit movement thereof.

Referring now particularly to Figure 4 of the drawings, it will be observed that the indicator disc 14 is formed in two parts. The outer part 35 comprises a disc 30 of insulating material such as "Bakelite" while the other part 31 comprises a metallic disc that is formed integrally with a hub 32. The hub 32 projects through an aperture 33 in the face plate 11 and in a metallic 40 frame plate 34 which is secured to the rear thereof.

It will be noted that the control arm 27 is provided with a slotted opening 35 to permit radial movement of the control arm 27 with respect to 45 the hub 32. A bushing or sleeve 36 is provided around the hub 32 and within the slotted opening 35. The control arm 27 is biased to the position shown in Figure 4 by means of a coil compression spring 37 which reacts between the outer 50 surface of the bushing 36 and the inner end of a screw 38 which is threaded into the control arm 27 as shown. A washer 39 is located around the hub 32 and between the control arm 27 and the face of the disc 30 forming a part of the indicating disc 14.

Underneath the knob 29 on the control arm 27 there is provided a generally semi-circular detent 40 which is arranged to interfit with any one of the semi-circular openings 45 in the indicating disc 14. It will now be apparent that the coil compression spring 37 will bias the control arm 27 radially with respect to the hub 32 so as to hold the semi-circular detent 40 in any one of the semi-circular openings 45 in which it may be positioned. In order to move the control arm 27 from one position to another it is necessary to move it radially outwardly and compress the spring 37 sufficiently far to permit the semi-circular detent 40 to clear the outer periphery of the indicating disc 14. It is then possible to move the control arm with respect to the indicating disc 14 to any desired position.

The control arm 27 is also provided with a radially outwardly extending detent 41 which is best shown in Figure 2 of the drawings. The detent 41 is arranged to engage the cam surface 22 of the cam member 19 when the indicating disc 14 is rotated in a counterclockwise direction and to prevent further rotation thereof when it engages the stop 18. In moving into engagement with the stop 18 the cam member 19 is lifted by the detent 41 to perform a control function which will be described hereinafter. As shown more clearly in Figure 4 of the drawings, the hub 32 is secured by set screws 42 to a shaft 43 which is mounted at its rear end in a bearing 44 that is carried by a frame plate 45, similar to the frame plate 34. A bracket 46, Figure 3, secured to the rear frame plate 45 serves to support the forward end of the shaft 43. The frame plates 34 and 45 are spaced apart by means of pillars 47 to which they are secured by suitable countersunk screws, as shown.

Secured to the shaft 43 is a spring washer 48 which is arranged to have frictional engagement with a friction disc 49 that is carried by a drum 50 which is mounted for rotation freely on the shaft 43. A collar 50' secured by a set screw 50'' to the shaft 43 holds the drum 50 against the friction disc 49.

With a view to preventing undesired rotation of the shaft 43, brake means are provided for frictionally restraining the movement of the drum 50. For this purpose brake shoes 51 are provided on opposite sides of the drum 50. As shown in Figure 3, the brake shoes 51 are formed by properly shaping a single strip of metal. They are secured to the frame plate 45 by a screw 52. Brake lining 53, Figure 4, is provided for each of the brake shoes 51 to provide the brake surface for engaging the drum 50.

Secured to the drum 50 is a ratchet wheel 56, Figure 3, which is arranged to be advanced in a step-by-step manner by a pawl 57 that is carried at the outer end of an arm 58. A pair of guide members 59 carried on opposite sides of the arm 58 interfit with the ratchet wheel 56 and insure the proper cooperation between the pawl 57 and the teeth of the ratchet wheel 56. The stroke of the pawl 57 is limited by a pin 60 which is carried by a plate 61 which is secured to the rear frame plate 45.

A locking pawl 62 is pivoted at 63 in a bracket 64 that is carried by the rear frame plate 45 and it is arranged to cooperate with the teeth of the ratchet wheel 56 to prevent retrograde movement thereof. A coil tension spring 65 interconnects the arm 58 and the locking pawl 62 for biasing them into operative positions.

The arm 58 is pivoted at 66 at the upper end of a lever 67 whose initial position is determined

by an adjusting screw 68. A coil tension spring 69 serves to bias the lever 67 in a clockwise direction for withdrawing the pawl 57 from the ratchet wheel 56. The lever 67 is pivoted at 70 in a bracket 71 that is carried by the rear frame plate 45. A link 72 connects the lever 67 and an armature 73 which is arranged to be attracted by a winding 74 that is intermittently energized in a manner which will be described hereinafter.

It will be recalled that the cam member 19, Figure 1, has been previously described as being mounted on means which projects through an aperture 20 in the insulating plate 11 and the front frame plate 34. As shown in Figure 4 of the drawings, the cam member 19 is mounted on a stud 77 which is carried by a lever 78 that is pivoted at 79, Figure 3, on an insulating block 80 that is secured to the rear side of the front frame plate 34. The stud 77 is provided with a sleeve 81 of insulation which engages the under surface of a contact finger 82, Figure 4, that is biased downwardly by a coil tension spring 83. The contact finger 82 is pivoted at 84 in a bracket 85 that is carried by the insulating block 80.

As is shown in Figure 3 of the drawings, the contact finger 82 carries a contact button 86 which is arranged to engage a similar contact button 87 that is carried by a metal bracket 88 which is mounted on the insulating block 80. The bracket 88 serves as one terminal to which a conductor 89 can be connected. Another conductor 90 is connected to a terminal plate 91, also carried by the insulating block 80, and it is connected by a conductor 92 to the bracket 85, thereby providing a circuit connection to the contact arm 82.

As previously set forth, when the detent 17 occupies the position shown in Figure 1 of the drawings in engagement with the stop 18, the cam member 19 is lifted. In this position the contact finger 82 is lifted since the stud 77 is in its upper position. Consequently the contact button 86 is out of engagement with the contact button 87, as shown in Figure 3 of the drawings.

On energization of the winding 74, the core 73 is attracted and the lever 67 is moved in a counterclockwise direction, carrying with it the pawl 57 which engages one of the teeth of the ratchet wheel 56 and advances the latter one notch. This movement is transmitted through the friction disc 49 and spring washer 48 to the shaft 43 on which the indicating disc 14 is mounted for rotation with the hub 32. The detent 17, which is carried by the indicating disc 14, moves along the cam surface 21 of the cam member 19 and permits the latter to be lowered under the influence of the coil tension spring 83, Figure 4, so that contact button 86 engages contact button 87 and a circuit is completed for performing a certain operation which will be described hereinafter.

The continued intermittent energization and deenergization of the winding 74 causes the pawl 57 to step the ratchet wheel 56 around until the detent 41, Figure 2, on the control arm 27 engages the cam surface 22 and further movement is arrested on engagement with the stop 13, Figure 1. Further intermittent energization of the winding 74 merely causes the ratchet wheel 56 to advance but no further movement is transmitted to the shaft 43 because of the friction coupling provided between the spring washer 48 and the friction disc 49.

The extent of movement of the indicating disc 14 and the control arm 27 associated therewith, of course, depends upon the relative position of

the latter with respect to the former. As indicated, anywhere from one to twenty-five successive energizations and deenergizations of the winding 74 may be required to first effect the closure of the circuit through the contact buttons 86 and 87 and its subsequent opening there-between.

The counting mechanism, previously described, may be employed for various purposes. For example, it can be employed in connection with the testing of watthour meters as disclosed in the copending application of Robert J. Bushnell, Serial No. 353,156, filed August 19, 1940, now Patent No. 2,241,181. For such an application it is desired to count the number of revolutions of the disc of a standard test meter which is employed for checking the operation of the meters being tested. When the revolutions of the disc of such a meter are to be counted, it is desirable to use some means which will not affect in any way the operation of the meter. For this reason it is desirable to use some inertialess means such as the interception of light rays for controlling the counting mechanism. Ordinarily it is difficult to arrange the light transmitting and light sensitive apparatus on the opposite sides of the disc of the test meter for the reason that the operating windings, frame, and magnets interfere with the application of such equipment. According to my invention as herein disclosed, I have provided for utilizing this inertialess means for controlling the counting mechanism in such a way as to not interfere with the construction of the standard test meter. Moreover, a minimum of modification of the meter construction is required in order to adapt it for use in conjunction with the control apparatus.

In Figure 5 of the drawings, there is illustrated diagrammatically the arrangement of the counting mechanism of this invention with a watthour meter disc construction also modified in accordance with the present invention. As there shown, the disc is indicated at 96 and is mounted on a shaft 97 which can be driven by any suitable disc driving means 98. Of course, it will be understood that, in a watthour meter construction, the disc driving means 98 would be the current and voltage elements of the meter. However, the present invention is not limited to this particular driving means and, accordingly, any other suitable or desired driving means can be substituted as desired. Mounted for rotation with the disc 96 is a sleeve 99 having registering apertures 100 therein. The rays of light from a light source 101 are arranged to be intercepted by the sleeve 99 so that they will not fall on a photo-electric cell 102 except when the apertures 100 are in alignment, as shown in Figure 5 of the drawings, directly between the light source 101 and the photo-electric cell 102. By placing the light source 101 on one side of the disc 96 and substantially in its plane of rotation and similarly placing the photo-electric cell 102 on the opposite side, no interference results with the mechanism above and below the disc 96 which is customarily employed for driving the same.

The light source 101 can be energized from any suitable source of current such as the source indicated at 103 which may be a 60-cycle, 110 volt source. The source 103 is also employed for energizing the winding 74 of the counting mechanism and certain other apparatus as will be presently set forth.

The output of the photo-electric cell 102 is amplified by an amplifier of conventional con-

struction indicated at 104, which is arranged to control the energization of a winding 105 of a control relay 106. It will be understood that, when the apertures 100 are so positioned as to permit light from the source 101 to impinge upon the photo-electric cell 102, then the winding 105 will be energized. As soon as further movement of the disc 96 cuts off the light rays from the photo-electric cell 102, the winding 105 is promptly deenergized.

The relay 106 is provided with normally open contact members 107 which are closed on energization of the winding 105. When the contact members 107 are closed, an energizing circuit for the winding 74 is completed from the source 103 which is obvious and will not be traced. As previously described, when the winding 74 is energized, the core 73 is attracted and the pawl 57 advances the ratchet wheel 56.

The first advance of the ratchet wheel 56 moves the detent 17 away from the stop 18 and over the cam surface 21, thereby permitting the contact finger 82 to move downwardly until the contact button 86 engages the contact button 87. A circuit is then completed for energizing a controlled device indicated at 108. The controlled device 108 may be a relay or similar other electromagnetically operated device as will be readily understood. A conductor 109 serves to connect it to the source 103.

As long as the contact button 86 engages the contact button 87, the controlled device 108 will be energized. This will continue until the detent 41 engages the cam surface 22 and lifts the contact finger 82 so that these contact buttons are separated. The controlled device 108 is then deenergized.

Since certain changes can be made in the foregoing construction and different embodiments of the invention can be made without departing from the scope thereof, it is intended that all matter as shown in the accompanying drawings or described hereinbefore shall be interpreted as illustrative and not in a limiting sense.

45 I claim as my invention:

1. Counting apparatus comprising, in combination, means for causing current to flow in a circuit as a series of impulses, a ratchet wheel, pawl means cooperating with said ratchet wheel, electromagnetic means disposed to be energized each time an impulse is received for moving said pawl means to effect corresponding movement of said ratchet wheel, a movable member having a fixed initial position, clutch means operatively interconnecting said ratchet wheel and said movable member, a contact arm and a cooperating contact member, means operatively connecting said contact arm to said movable member whereby in said initial position thereof it occupies one position with respect to said contact member and is moved to an alternate position on movement of said movable member from its initial position on the initial energization of said electromagnetic means, and means operated by said movable member for returning said contact arm to its said one position when said movable member has been operated to a predetermined position after receipt of a predetermined number of impulses.

2. In counting apparatus, in combination, a driven member, stop means for arresting said driven member in an initial position, a drive member, friction clutch means interconnecting said members for driving said driven member in one direction away from said stop means and

permitting rotation of the same in the opposite direction, a ratchet wheel fast on said drive member, a pawl cooperating with said ratchet wheel, a spring for retracting said pawl, an armature operatively connected to said pawl, a winding disposed to be energized by a series of electrical impulses for attracting said armature and operating said pawl to advance said ratchet wheel and drive member and driven member one notch for each impulse, a member movable from one position to another, means carried by said driven member for causing said movable member to shift from said one position on movement of said driven member from its initial position, additional means carried by said driven member for causing said movable member to shift back to said one position after said driven member has been rotated through a predetermined extent corresponding to a predetermined number of impulses, and manual means on said driven member for resetting the same to its initial position against said stop means.

3. In counting apparatus, in combination, a driven member having predetermined initial position, a drive member, friction clutch means interconnecting said members for driving said driven member in one direction and permitting rotation of the same in the opposite direction, a ratchet wheel fast on said drive member, a pawl cooperating with said ratchet wheel, a spring for retracting said pawl, an armature operatively connected to said pawl, a winding disposed to be energized by a series of electrical impulses for

attracting said armature and operating said pawl to advance said ratchet wheel and drive member and driven member one notch for each impulse, a contact arm and a cooperating contact member 5 stop means carried by said contact arm, an indicator disc fast on said driven member and having a corresponding initial position, a scale on said disc, a lug on said disc adapted to engage said stop means and hold said contact arm in one 10 position with respect to said contact member when said disc is in its initial position and to effect movement of said contact arm to an alternate position with respect to said contact member when said disc moves from its initial position 15 on receipt of the first impulse, a control arm adjustably mounted on said driven member and movable with respect to said disc and said scale thereon to different positions corresponding to different numbers of impulses, means operatively 20 interconnecting said control arm and said disc whereby the former is held in any position to which it may be adjusted with respect to the latter, a lug on said control arm adapted to engage said stop means on receipt of the last of a series 25 of impulses for preventing further movement of said driven member from said drive member and moving said contact arm back to said one position, and manual means on said driven member for resetting the same to its initial position with the lug on said disc abutting said stop means.

VIRGIL S. HARDEY.
